UNITED STATES PATENT OFFICE.

CHARLES W. KELLY, OF JASPER, ALABAMA

LABELING-MACHINE

No. 870,182.

Specification of Letters Patent.

Patented Nov. 5, 1907.

Application filed June 8, 1906. Serial No. 820,877.

To all whom it may concern:

Be it known that I, CHARLES W. KELLY, a citizen of the United States, residing at Jasper, in the county of Walker and State of Alabama, have invented certain new and useful Improvements in Labeling-Machines, of which the following is a specification.

This invention consists of a machine designed particularly for use in large factories, or any similar capacity, for applying labels to cans, bottles, or similar receptacles.

The machine includes in its organization peculiar mechanism for applying paste to the labels, for attaching the labels to the receptacles to be labeled, and other general operating mechanism such as is necessary in a machine of this class.

For a full description of the invention and the merits thereof and also to acquire a knowledge of the details of construction of the means for effecting the result, reference is to be had to the following description and accompanying drawings, in which:

Figure 1 is a side elevation of a labeling machine embodying the invention. Fig. 2 is a view similar to Fig. 1, looking from the other side of the machine. Fig. 3 is a vertical longitudinal sectional view. Fig. 4 is an end view of the machine. Fig. 5 is a horizontal sectional view taken just above the top of the stand and showing the operating mechanism coöperating with the receptacles, and adjacent parts, in top plan view. Fig. 6 is a top plan view of the ratchet mechanism for feeding the labels upwardly in the label magazine. Fig. 7 is a sectional view through the paste box bringing out more clearly the arrangement of the paste feeding devices. Fig. 8 is a perspective view of the paster and the label removing or ejector mechanism. Fig. 9 is a perspective view of certain of the operating parts and connections used for actuating the several mechanisms. Fig. 10 is a detail perspective view of the roller having the cam slot and parts connected therewith. Fig. 11 is a view bringing out more clearly the flexible connections which impart rotary movement to the grippers as they are actuated. Fig. 12 is a detail view showing the manner of mounting the retarding fingers and coacting parts.

Corresponding and like parts are referred to in the following description and indicated in all the views of the drawings by the same reference characters.

Referring to the drawings, and specifically describing the machine, the numeral 1 indicates a suitable substantial stand on which the parts of the mechanisms embodied in the machine are carried and which may be of any desired construction. The stand 1 carries a frame-work composed of a number of uprights 2 attached to the bars of the stand 1 in a substantial manner. Beneath the top portion of the stand 1 is located the label magazine 3, the latter being adapted to receive the labels in a stack, from which they are removed when

being applied to the receptacles. The magazine 3 is of box-like form and the outer side thereof is removable to admit of placing a supply of labels in position, whenever necessary. A vertically movable follower 4 is arranged in the magazine 3 and is operable in its vertical movement by a threaded rod 5, the upper end of which is secured to said follower. In order to move the rod 5 vertically and gradually elevate the follower 4, as the labels are being fed from the magazine 3, a ratchet wheel 6 is provided, said wheel having an opening therein through which the rod 5 passes. The wheel 6 is arranged above a cross bar 7 attached to the lower bars of the stand 1 and said ratchet wheel is formed on its upper side with a plurality of radial ratchet teeth 8 adapted to be engaged by a pawl 9 pivotally connected with a lever 10. The pawl 9 is provided with a plurality of openings so as to admit of adjustment of its pivotal connection with the lever 10 whereby to regulate the movement of the ratchet wheel under its actuation so as to cause the stack of labels in the magazine 3 to be fed upwardly more or less slowly. In the upper or toothed face of the wheel 6, is formed a socket which receives complementary plates 11 adapted to be readily separated when removed from the socket of the wheel 6, but resting in contact with one another when in position in such socket. The meeting faces of the plates 11 are formed with recesses which are threaded and which when registering constitute virtually a threaded opening through which the rod 5 passes. The use of the plates 11 is to permit of ready detachment thereof from the rod 5 in order to lower said rod and the follower 4 in renewing the supply of labels in the magazine 3 after the follower 4 has been forced to the limit of its upward movement.

The lever 10 by which the wheel 6 is operated, is connected at its lower end by a rod 12 with one of a pair of levers 13 which are pivoted at the lower extremities thereof, as shown at 14, to side bars of the stand 1. The upper end portions of the levers 13 are connected by members 15 with slidably mounted bearing blocks 16, in which are mounted two gripper shafts 17. Each gripper shaft 17 is mounted on a pair of the blocks 16, and said blocks 16 are adapted for longitudinal movement upon the stand 1, when actuated by the members 15 attached to the levers 13. One pair of the blocks 16 is arranged for movement at one side of the top of the magazine 3, while the other pair of blocks is similarly arranged at the other side of the magazine. In like manner two frames 18 are located at opposite sides of the top portion of the magazine 3, said frames comprising longitudinal rods 18^a and cross or connecting bars 18^b which connect opposite ends of the rods 18^a. Each frame 18 is fixed from longitudinal movement, but is adapted for lateral movement in order to cause grippers 19, mounted on the inner adjacent ends of the shafts 17, to move to-

ward each other to grip the receptacle which is to be carried across the open upper end of the magazine 3 in order to apply the label thereto.

To effect the desired movement of the frames 18 and the grippers 19 actuated thereby, which grippers consist preferably of disks secured rigidly to the adjacent ends of the shafts 17, actuating rods 20 are used, said rods being connected at the outer ends thereof with cranks 21 on a shaft 22. The shaft 22 has a third crank 23 projecting therefrom intermediate of its ends, and said shaft is located at one end of the stand 1 and transversely with reference thereto. The crank 23 is connected with the upper end of a pitman rod 24, said pitman being composed of spaced parts between the lower end portions of which are mounted two spaced rollers 25. The spaced rollers 25 receive an eccentric disk 26 therebetween, the said disk being mounted on a double crank shaft 27. The shaft 27 is mounted in suitable bearings at the end of the stand 1 at which the shaft 22 is located and the double crank 28 of the shaft 27 is connected by a pitman 29, of T-form, with the pair of levers hereinbefore described. In other words, it will be seen that the shaft 27 actuates the bearing blocks through the levers 13 and members 15. Said shaft 27 also actuates the frames 18 through the rods 20 and pitman rod 24. The rods 20, by which the frames 18 are moved laterally, or toward and from each other, have the inner ends thereof pivotally attached to the outer pivotally connected ends of a pair of toggle links 30 and 31, which directly operate the frames 18. One pair of toggle links 30 and 31, for each frame 18, is directly connected with the rods 20 and these pairs of links 30 and 31 are located at the ends of the frames 18 which are nearer the shaft 22. A pair of similar toggle links, indicated 30^a and 31^a is located at the opposite end of each frame 18, being connected with said frame 18 in the same manner as the links 30 and 31, the outer pivotally connected ends of the links 30^a and 31^a, however, being connected by rods 32 to the points of pivotal connection of the outer ends of the links 30 and 31. The pairs of links at the opposite ends of each frame 18 are therefore connected together for simultaneous movement by a rod indicated at 32. The links 31 and 31^a of each pair of links above described, have one end pivoted to the frame-work of the stand 1, at 33, the opposite end being pivotally connected at 34 with the outer ends of the links 30 and 30^a as before mentioned. The inner ends of the links 30 and 30^a are pivotally connected, however, with the central portions of the cross bars 18^b of the frames 18. It will be apparent from the foregoing that when the rods 20 have longitudinal movement imparted thereto, pivotal movement will be imparted to the links 30^a and 31^a. Movement of the rods 20 in one direction will thus so actuate the links 30 and 30^a and 31 and 31^a as to force the frames laterally and toward each other; or in an opposite direction, away from each other.

An inclined supply chute 35 is located at one end of the stand 1 and supplies the receptacles to be labeled, to the gripping and labeling mechanism. The lower end of the chute 35 terminates at a point adjacent to the normal positions of the grippers 19 and as a receptacle passes from the chute 35, the mechanism is so timed that the rods 20 will be actuated to force the

frames 18 toward each other and move the grippers 19 in a similar direction so that the latter will engage opposite ends of the receptacle or can. As soon as the grippers 19 engage the can or receptacle, indicated 36, the levers 13 move so as to force the bearing blocks 16 longitudinally of the rods 18^b of the frames 18 to thereby carry the gripper shafts 17 and the grippers 19 away from the inner end of the chute 35. This movement of the grippers causes them to carry the can or receptacle engaged thereby, across the upper open end of the magazine 3, and the uppermost label of the stack in the magazine is applied to the can in this movement thereof, said label having previously been provided with paste or adhesive material, by pasting mechanism to be hereinafter described. The can or receptacle 36 engaged by the grippers 19, and being carried across the open end of the magazine 3 thereby, is revolved in its movement in order to facilitate the application of the label to be pasted thereon. The revolution of the receptacle as above mentioned, is effected by rotation of the grippers 19 and such rotation is caused by flexible connections such as tapes or wires 37, which are attached at their ends to the frame-work of the machine and which have intermediate portions passing about grooved wheels 38 mounted on the outer end portions of the gripper shafts 17. In the movement of the grippers longitudinally of the frames 18, the flexible connections 37 rotate the wheels 38, which are fixed on shafts 17 and necessarily impart similar movement to the grippers 19. 95

Retarding mechanism is employed to hold the receptacle in the chute 35, as one of said receptacles is being carried across the magazine 3 in applying a label thereto. This retarding mechanism consists of a plurality of retarding fingers 39, which are vertically movable at that side of the magazine 3 adjacent to the shaft 22. Normally, the retarding fingers 39 are held in such a position that they project upwardly from the bottom of the chute 35 to thereby prevent the lowermost can in said chute from moving from the position assumed thereby just previous to such can being gripped by the grippers 19. However, as the grippers 19 are returning to the positions initial to gripping the can to be next carried across the magazine and labeled, a bar 40 having a hook 41, is actuated and imparts movement to a bell-crank 42, which crank is connected with the lower portions of the retarding fingers 39, such movement of the bell-crank pulling downwardly upon the fingers 39 to force said fingers out of the way of the can which is gripped by the grippers 19 which start to carry said receptacle to the labeling mechanism. A spring 43 is connected with the fingers 39 and normally holds said fingers projected upwardly sufficiently to engage the receptacles fed from the chute 35. The hook 41 of the bar 40 is engaged by a transverse bar 44 which connects the levers 13, said levers being therefore responsible for the actuation of the retarding fingers 39 as hereinbefore set forth. 110

After the can or receptacle has been carried across the open end of the magazine 3 and the label applied thereto, the grippers 19 move apart after placing said can above a delivery belt 45, which constitutes a movable bottom for what is to be hereinafter termed as a compression chamber 46, through which the labeled can passes preliminary to its final delivery to the de- 130

livery-chute 47, which as shown, constitutes merely an inclined plane or bed. Obviously the delivery-chute 47 may lead to a box or the like so as to feed the labeled cans or receptacles to such box for packing therein. The belt 45 passes about a pulley 48 mounted on a shaft 49, said shaft 49 having a crank handle 50 by which it may be manually operated if desired.

The shaft 49, however, is supplied with a gear or sprocket 51, connected by a sprocket chain 52, passing about a second gear 53 on an end of the double crank shaft 27 and also about a third gear mounted on a shaft 55 carried in bearings applied to the lowermost longitudinal bars of the stand 1. The shaft 55 is supplied with a pulley by which it may be connected with a suitable motor, if it be desirable, and convenient, that the machine be driven by motor mechanism. The belt 45 also passes about a second pulley 57 mounted on a suitable shaft 58 located a short distance from the shaft 49. Above the belt 45 is disposed a spring-pressed plate 59 and this plate constitutes the top of the compression chamber 46. A longitudinal bar arranged above the plate 59 and substantially secured to the frame-work of the stand 1 and to the uprights 2, bears against the top ends of coiled springs 60, the lower end of which bear against the plate 59. Normally, the plate 59 is spaced from the belt 45, and said plate 59 exerts spring pressure upon the cans or receptacles 36 as the latter are delivered by the belt 45 from the compression chamber 46 to the out-chute 47. The under side of the plate 59 is preferably provided with a facing of rubber, fabric or soft material to facilitate the firm pressing of the label to the can after said label has been applied thereto. The parts 45 and 59 constitute therefore, both a delivery and compressing chamber, the advantages of which will be apparent from the foregoing.

The paste-applying mechanism used in connection with the mechanism hereinbefore set forth, is of a special construction, same being mounted a short distance above the label at the open end of the magazine 3. Said paste-applying mechanism consists of a paste-applying device or paster 61, which is mounted for vertical movement above the magazine 3 and which consists of a frame 62, to the under side of which are attached a plurality of pasting strips 63. The strips 63 are preferably provided upon the under sides thereof, with felt or similar material in order to more readily absorb the adherent substance forming the paste and more readily apply such adherent substance to the labels in the magazine 3, on descent of the paster 61. The advantage in making the paster in such a way that it is comprised of a number of strips 63, resides in the fact that any of the strips 63 may be removed or other strips substituted therefor, to increase or decrease the paste-applying surface as desirable according to the outline or form of the labels in magazine 3. The frame 62 is connected with a vertical frame 64, the top horizontal bar of the frame 64 being provided with two openings through which pass vertically movable rods 65. The rods 65 carry a plate 66 at the lower ends thereof, said plate being a part of the label removing or ejecting mechanism used in connection with the paster or paste-applying device 61. The sides of the frame 64 are preferably guided in the vertical movement of the frame 64 and the paster 61, by suitable guide members

67 applied to the upper end portions of the uprights 2. Rods 68 connect the cross bar at the upper end of frame 64 with cranks 69 extending from a shaft 70 mounted in vertical standards 71, which project upwardly from the upper extremities of a pair of uprights 2. The shaft 70 has a crank 72 extending from the end thereof and this crank is connected by a rod 73 with the shaft 27. The shaft 27 has another eccentric wheel 74 mounted thereon, adjacent to the inner side of the gear 53, and the lower end of the rod 73 has a roller 75 applied thereto to move in a grooved periphery of the wheel 74, such movement actuating the rod 73 and shaft 70. Paste is applied to the paster 61 by a paste applying roller 76, said roller being adapted to traverse the under surface of the strips 63 so as to renew the paste thereon at frequent intervals, just previous to the lowering or descent of the paster 61 in applying paste to the uppermost label in the magazine 3. The roller 76 is adapted to contact with a paste feeding roller 77 mounted in suitable bearings in the sides of a paste box 78, the paste feeding roller 77 being constantly rotated at a low rate of speed by connection with the operating mechanism of the machine. For the above mentioned purpose, one of the journals of the paste feeding roller 77 is extended through one side of the box 78 and has a ratchet wheel 79 mounted thereon and engaged by a pawl 80. The pawl 80 is pivoted to a short lever 81, which in turn is pivoted to the adjacent journal of the roller 77, said lever 81 being connected by a rod 82 with a bell-crank lever 83 at one side of the stand 1. The bell-crank lever is connected by a rod 84 with a crank wheel 85 mounted on the shaft 27. The roller 77 will thus be seen to be slowly moved all of the time the machine is being used. The box 78 is disposed at one side of an outermost pair of the uprights 2 and is suitably supported by braces 86. The paste-applying roller 76 is adapted for horizontal movement from the roller 77 to the under surface of the paster 61, and such horizontal movement is communicated to the roller 76 by the following means. Said roller 76 is journaled in the outer ends of horizontally slidable bars 87 and the inner ends of said bars 87 are connected with cranks 88 projecting from a shaft 89 mounted in suitable bearing and arranged above the paste box 78. Another crank 90 projects from the shaft 89, and is connected by a rod 91 with a bell-crank lever 92, said lever 92 being in turn connected with the lever 85 before mentioned, by the link 85 in order that motion may be imparted from the wheel 85 through the lever 92 to the shaft 89. From the foregoing, it will be clear that when the paster 61 is at the limit of its upward movement, the paste-applying roller 76 will be forced across and into contact with the under side of the paster just previous to the next descent of the latter to paste the uppermost label in the magazine 3. The supply of paste fed by the roller 77 to the roller 76 when the two are in contact, is regulated by suitable means secured by the provision of a movable bottom 93 for the box 78. The outer end of the bottom 93 of the box 78 is pivoted to the outer side of the box as shown at 94, while the inner end of the bottom 93 is arranged in contact with the peripheral portion of the roller 77 and is adjustably held in such contact by means of set-screws 95. The set-screws 95 pass through a cross bar 96 connecting opposite sides of the box 78 and by adjusting the set-screws 95, the bottom 93 can

be made to bear with greater or less pressure against the roller 77 to thereby regulate the feeding of the paste in the box as is desirable and as is necessary according to the actual conditions of use. The roller 77 occupies 5 the space at the inner side of the box, being substituted for such side removed, and constituting a closure for the paste, save as hereinbefore described.

The paster 61 descends in order to apply the paste to the uppermost label in the magazine 3 and as the pasting surface of the strips 63 is brought into contact with 10 the label, the whole upper side of the label, or a portion thereof, may be supplied with paste, as desired. In view of the construction of the invention, however, it is necessary to prevent the label in the magazine 3 from 15 being thrown upwardly by the paster 61 on ascent of the latter, due to adherence of the label and paster. The means provided for this purpose is comprised in the ejector or label remover which co-operates with the paster or paste-applying device 61 and which consists 20 of the plate 66, before described and a plurality of thin blades 97, which project downwardly from the lower side of said plate 66. As before described, the strips 63 are slightly spaced from one another and the spaces thus provided permit the blades 97 of the label ejector 25 or remover 66 projecting through the paster, to engage the label and press upon the same sufficiently to prevent adherence of the label and paster. The blades 97 preferably fit in slots in the plate 66 or they may be otherwise secured thereon and as said blades are very 30 thin, there is no likelihood of same adhering to the label, when the label ejector or remover is preventing adherence of the paster and label. The rods 65 which pass through the cross bar 64^a of the frame 64, support the label remover or ejector 66, springs 98 being coiled 35 about the upper ends of the rods 65 and bearing at the lower ends against pins 99 passing transversely through said rods. The upper end of the springs 99 bear against the under side of the cross bar 64^a. The normal tendency of the springs 98 is such as to project the blades 97 40 from the under side or pasting surface of the paster 61. Levers 100 are pivoted between their ends to short studs 101 projecting upwardly from the cross bar 64^a. One end of each lever 100 has pivotal connection with the upper end of one rod 65, and the outer end of each 45 lever is adapted to be engaged by a lateral arm 102 projecting from short vertical standards 103 carried by the upper frame-work supported by the uprights 2. In action, as the paster 61 descends to the label in the magazine 3, the blades 97 project from the 50 under or pasting surface of said paster. However, the paster moves down into contact with the upper surface of the label and applies the paste thereto, this movement being admitted of by the spring mounting of the blades 97 operated by the spring actuated rods 65.

55 When the pasting surface of the paster 61 is in contact with the label, the lower edges of the blades 97 are in a horizontal line with the pasting surface. As soon as the paster 61 begins to ascend, however, the blades 97 immediately move down so as to project from the under 60 side or pasting surface of the paster 61 and thus prevent adherence of the label with the paster, or in other words, remove the label from the pasting surface of the paste-applying device 61 aforesaid. The continued upward movement of the paster will disengage the blades 65 97 from the label as the label remover or ejector 66 is

carried by the paster. As the paster approaches its limit of upward movement, the levers 100 connected with the rods 65, are engaged by the outer ends thereof by the arms 102 and the rods 65 are moved upwardly so as to carry the blades 97 into such positions that they do 70 not project from the pasting surface of the paster 61. Immediately that the levers 100 have accomplished this action, the shaft 89 is actuated so as to operate the horizontally slideable bars 87 to carry the paste-applying roller 76 across the pasting surface of the paster 61 to 75 supply paste thereto. The blades 97 are withdrawn just in time to avoid interference with the roller 76 as it moves into contact with the pasting surface of the strips 63 of the paster 61. As soon as the roller 76 has applied the paste to the paster 61, the said roller moves laterally from the point beneath the paster so as to admit of the next downward descent of the latter, which immediately takes place.

A detailed explanation of the operation of the invention is unnecessary from the foregoing, but a general 85 description of such operation is herein given. As the machine is being operated either by motor or manually, the cans or receptacles to be labeled, are fed from the chute 35 governed only by the retarding fingers 39. The grippers 19 engage the receptacles as soon as they 90 leave the chute 35 and carry the receptacle across the open end of the magazine 3 in contact with the label uppermost therein. This label has been previously supplied with paste upon its upper side, by descent of the paster 61 thereon, and the grippers 19 being revolved in traveling over the pasted label, the latter is readily wrapped thereabout. The label having been applied to the receptacle, the grippers 19 force the receptacle into the compression chamber 64, whereupon it is delivered to the out-chute 47 by the delivery belt 100 45, the compression plate above the belt 45 firmly effecting adherence of the label with the receptacle.

Having thus described the invention, what is claimed as new is:

1. In a labeling machine, the combination of a label 105 magazine, a paster movable towards the magazine to apply paste to the labels therein, a paste applying roller, means for passing said roller across the pasting surface of the paster to apply paste thereto, means adapted to project past the pasting surface of the paster to prevent adhesion of the label thereto, and means for retracting said last named means from the pasting surface of the paster preparatory to passing the roller over such surface.

2. In a labeling machine, the combination of a label 115 magazine, a paster movable towards the magazine to apply paste to the labels therein, means for passing a receptacle across the magazine to apply a label thereto, a spring pressed label removing device adapted to prevent the adhesion of a label to the paster, when the latter is withdrawn from the magazine, means for retracting said label removing device to a position above the pasting surface of the paster during the withdrawal of the latter from the magazine, and means for applying paste to said surface with the label removing device in its retracted position.

3. In a labeling machine, the combination of a label 125 magazine, means for carrying the receptacles across the magazine to apply a label thereto, a paste applying device adapted to move downwardly into contact with the uppermost label in the magazine, and embodying a series of spaced pasting strips, plates normally projecting beyond 130 the pasting surface of said strips, and movable in spaces between the latter, said plates being spring pressed in a downward direction, means for raising the paster from the magazine, means for retracting the plates from the pasting surfaces of the strips during the rising movement of the 135

1. paster, a paste applying roller adapted to pass over pasting surfaces of said strips with a movement at right angles to the movement of the paster, means for passing said roller back and forth over the said surface with the label removing device in retracted position, and means for automatically releasing the said label removing device from such retracted position in the downward movement of the past. 85
2. In a labeling machine, the combination of a label magazine open at its upper end and adapted to receive labels in stack, receptacle supply means, grippers for engaging and carrying a receptacle across the open end of the magazine to apply a label thereto, pasting mechanism for the labels, levers operably connected with the grippers 10 to effect movement thereof, and means for feeding labels upwardly in the magazine operated by said levers. 90
3. In a labeling machine, the combination of receptacle supply means, label supply means, means for pasting the labels grippers arranged to engage the receptacles and apply them to the labels, means for imparting rotary movement to the receptacles as the labels adhere thereto, and means for delivering the receptacles from the machine embodying a traveling belt arranged to continue the rotary movement of the receptacles after same have been 15 delivered from the grippers, and a compression plate cooperating with said delivery belt. 95
4. In a labeling machine, the combination of a label magazine open at its upper end, a vertically movable paste-applying device above the label magazine, a receptacle supply chute, rectilinearly operating grippers movable across the open end of the magazine and below the paste-applying mechanism and arranged to effect application of a label to the receptacle, means for delivering the labeled receptacles from the machine, a label remover or ejector device cooperating with the paste-applying device, said label remover embodying a plurality of elements normally projecting from the paste-applying surface of the paste applying device, and spring pressure means cooperating with the label remover or ejector device. 100
5. In a labeling machine, the combination of a label magazine open at its upper end, a vertically movable paste-applying device above the label magazine, a receptacle supply chute, rectilinearly operating grippers movable across the open end of the magazine and below the paste-applying mechanism and arranged to effect application of a label to the receptacle, means for delivering the labeled receptacles from the machine, a label remover or ejector device cooperating with the paste-applying device, said label remover embodying a plurality of elements normally projecting from the paste-applying surface of the paste applying device, and spring pressure means cooperating with the label remover or ejector device. 105
6. In a labeling machine, the combination of a label magazine open at its upper end, a vertically movable paste-applying device above the label magazine, a receptacle supply chute, rectilinearly operating grippers movable across the open end of the magazine and below the paste-applying mechanism and arranged to effect application of a label to the receptacle, means for delivering the labeled receptacles from the machine, a label remover or ejector device cooperating with the paste-applying device, said label remover embodying a plurality of elements normally projecting from the paste-applying surface of the paste applying device, and spring pressure means cooperating with the label remover or ejector device. 110
7. In a labeling machine, the combination of a label magazine open at its upper end, a vertically movable paste-applying device above the label magazine, a receptacle supply chute, rectilinearly operating grippers movable across the open end of the magazine and below the paste-applying mechanism and arranged to effect application of a label to the receptacle, means for delivering the labeled receptacles from the machine, a label remover or ejector device cooperating with the paste-applying device, said label remover embodying a plurality of elements normally projecting from the paste-applying surface of the paste applying device, and spring pressure means cooperating with the label remover or ejector device, means for applying paste to the pasting surface of the pasting device, and means for withdrawing the elements of the label remover or ejector device from the projected positions normally assumed thereby. 115
8. In a labeling machine, the combination of a label supply means, label pasting mechanism including a paster movable to apply paste to a label, means for actuating the paster, receptacle supply means, means for applying the label to a receptacle, a label remover or ejector device for preventing adherence of the labels with the paster and movable with said paster, and means for actuating the ejector device independently of the paster. 120
9. In a labeling machine, the combination of receptacle supply means, label applying mechanism, pasting mechanism including a vertically movable paster, a label remover or ejector device for preventing adherence of a label with the paster and comprising a plurality of blades adapted to project from the pasting surface of the paster, means for holding said blades normally projected from the pasting surface of the paster, means for withdrawing the blades from the pasting surface of the paster on ascent of the latter, and means for supplying the paster with paste when the ejector blades are withdrawn. 125
10. In a labeling machine, the combination of receptacle supply means, label applying mechanism, pasting mechanism including a vertically movable paster, a label remover or ejector device mounted on the paster and comprising a plurality of blades, spring means cooperating 130
11. with the blades to normally project the same from the pasting surface of the paster, trip means for withdrawing the blades from the projected positions on ascent of the paster, and means for supplying the pasting surface of the paster with paste when the blades of the ejector device have been withdrawn. 135
12. In a labeling machine, the combination of receptacle supply means, label applying mechanism, pasting mechanism including a vertically movable paster, a label remover or ejector device mounted on the paster and comprising a plurality of blades, spring means cooperating with the blades to normally project the same from the pasting surface of the paster, trip means for withdrawing the blades from the projected positions on ascent of the paster, means for supplying the pasting surface of the paster with paste when the blades of the ejector device have been withdrawn, the last mentioned means consisting of a paste-applying roller movable across the pasting surface of the paster, a paste receptacle, and a paste feeding roller for contact with the paste applying roller. 140
13. In a labeling machine, the combination of receptacle supply means, label supply means, means for supplying paste-to-the labels, means for supplying the labels to the receptacles including a gripper, a frame having said gripper slidably mounted thereon, means for effecting sliding movement of the gripper on the frame, and means for actuating said frame to effect engagement of the gripper with the receptacle. 145
14. In labeling machine, the combination of receptacle supply means, label supply means, means for applying the labels to the receptacles including a pair of grippers, a pair of frames having the grippers slidably mounted thereon, means for actuating the grippers to effect movement thereof longitudinally of the frames, and means for effecting lateral movement of the frames to cause engagement of the grippers with receptacle. 150
15. In a labeling machine, the combination of receptacle supply means, label supply means, means for applying the labels to the cans consisting of a pair of grippers, a pair of frames arranged horizontally, means slidably connecting the grippers with the frames, means for effecting lateral movement of the frames to cause engagement of the grippers with a receptacle, means for imparting longitudinal movement of the grippers on the frames to apply the labels to the receptacles, and means for imparting rotary movement to the grippers in the last mentioned operation. 155
16. In a labeling machine, the combination of receptacle supply means, label supply means, means for applying the labels to the cans consisting of a pair of grippers, a pair of frames arranged horizontally, means slidably connecting the grippers with the frames, means for effecting lateral movement of the frames to cause engagement of the grippers with a receptacle, means for imparting longitudinal movement of the grippers on the frames to apply the labels to the receptacles, wheels connected with the grippers, and flexible connections connected with the wheels of the grippers to impart rotary movement thereto by unwinding therefrom. 160

In testimony whereof, I affix my signature in presence of two witnesses.

CHARLES W. KELLY. [L. S.]

Witnesses:

JONAS BOSHELL,
W. C. INMAN.
